[57] CLAIM

The ornamental design for a air refreshening ventilated toilet seat, as shown.

DESCRIPTION

FIG. 1 is a left side elevational view of the air refreshening ventilated toilet seat of the present invention;

FIG. 2 is a right side elevational view of the air refreshening ventilated toilet seat of FIG. 1;

FIG. 3 is a front elevational view of the air refreshening ventilated toilet seat of FIG. 1;

FIG. 4 is a back elevational view of the air refreshening ventilated toilet seat of FIG. 1;

FIG. 5 is a top plan view of the air refreshening ventilated toilet seat of FIG. 1;

FIG. 6 is a bottom plan view of the air refreshening ventilated toilet seat of FIG. 1; and,

FIG. 7 is a perspective view of the air refreshening ventilated toilet seat of FIG. 1.

The broken line showing is for illustrative purposes only and forms no part of the claimed design.
